DESIGN FOR A BOTTLE CAPPER CASING OR THE LIKE

Eugene W. Weston, Elginburgh, Ontario, Canada

Application May 1, 1937, Serial No. 69,113

Term of patent 14 years

To all whom it may concern:

Be it known that I, Eugene W. Weston, a citizen of the Dominion of Canada, residing at Elginburgh, in the county of Frontenac and Province of Ontario, have invented a new, original, and ornamental Design for Bottle Capper Casings or the like, of which the following is a specification, reference being had to the accompanying drawing, forming part thereof.

Fig. 1 is a front elevation of a bottle capper casing, or the like, showing my new design.

Fig. 2 is a side elevational view thereof.

Fig. 3 is a cross-sectional view taken through the standard just below the glass enclosure, and looking down.

The dominant features of my design reside in the portions shown in full lines.

I claim:

The ornamental design for a bottle capper casing or the like, as shown and described.

EUGENE W. WESTON.
